UNITED STATES PATENT OFFICE.

EDGAR W. ANTHONY, OF BROOKLINE, AND HERBERT W. BEATTIE, OF QUINCY, MASSACHUSETTS, ASSIGNEES TO SMITH AND ANTHONY COMPANY, OF BOSTON, MASSACHUSETTS.

DESIGN FOR A RANGE OR COOKING-STOVE.

SPECIFICATION forming part of Design No. 34,286, dated March 26, 1901.

Application filed February 25, 1901. Serial No. 48,857. Term of patent 14 years.

To all whom it may concern:

Be it known that we, EDGAR W. ANTHONY, of Brookline, and HERBERT W. BEATTIE, of Quincy, in the county of Norfolk and State of 5 Massachusetts, citizens of the United States, have invented and produced a new and original Design for Ranges or Cooking-Stoves, of which the following is a specification, reference being had to the accompanying drawing, 10 forming a part thereof.

The invention relates to a design for ranges and cooking-stoves. It is represented in the drawing as applied to the base, the oven-door, the oven-shelf, the fire-pot door, the ash-pit front, including the broiler-door and ash-pit door, the stove-shelf, the elevated shelves, and their back plates, while indications of the design are also found in the hearth-plate. The base comprises the sides and the legs, 15 each of which have upon or in them the characteristic features or elements of the figure which comprises the ornamentation and which in certain of the parts of the range or stove is combined with a heavy curved border-scroll upon the edge of said part or parts. The ornamentation comprises a rich heavy large 20 curved leaf or spray molded deep into the surface rather than raised above it, so that a very rich, unusual, and effective blending of the 25 ornamentation with the plain portions of the

range is produced. The ornamentation of course is modified to adapt it to the particular part of the range or stove upon which it is used, so that the ornamentation in the legs varies in degree from the ornamentation on 35 the sides of the base, and the same is true of the ornamentation as applied to the other parts of the range or stove which we have named. They all have, however, the earmarks of the same type of figure or ornamentation, and the characteristic features of the ornamentation are readily distinguishable in all the various parts of the range or stove which are ornamented. 40

It would seem unnecessary in view of this 45 description to distinguish each ornamentation on each part of the range shown in the drawing by a reference-letter. The drawing very well shows the nature of the ornamentation.

Having thus fully described our design, we 50 claim and desire to secure by Letters Patent of the United States—

The design for a range or cooking-stove substantially as herein shown and described.

EDGAR W. ANTHONY.
HERBERT W. BEATTIE.
